UNITED STATES PATENT OFFICE.

ROBERT A. McCALL, OF MORGANTOWN, WEST VIRGINIA.

DRYING RACK.

Application filed March 20, 1928. Serial No. 263,150.

This invention is a drying rack for general use in households, laundries, dressing rooms, and various other places where such racks may be conveniently employed.

One of the objects of the invention is to provide a simple form of rack which may be conveniently supported for ready access, and so constructed that it will not require much space for storage when not in use. A further object is to provide a rack of the character referred to, provided with means for firmly and efficiently gripping the article to be supported, so that said article will not be accidentally disengaged and yet may be readily released when desired.

The invention will be hereinafter fully set forth and particularly pointed out in the claims.

In the accompanying drawings:

Figure 1 is a side elevation of a rack constructed in accordance with the invention, illustrating one method of supporting the same. Figure 2 is a front view thereof. Figure 3 is a top plan view. Figure 4 is an enlarged sectional view on the line 4-4 of Figure 3. Figure 5 is an enlarged transverse sectional view of one of the rack bars illustrating one of the gripping devices. Figures 6 and 7 are top and front views respectively, illustrating the gripping device. Figure 8 is a sectional view illustrating a slight modification.

Referring to the drawings, 10, 10 designate a plurality of support bars constructed of any desired material, and connected in spaced relation by means of cross rods 11, to provide a rack body. The said rack body may be supported in any suitable manner, as for instance by being pivoted at one end to a door frame, as indicated at 12, the free end being provided with a yoke 13, having a hook at one extremity thereof positioned to engage an eye 14, which is secured to an overhanging support, such as a ceiling (see Figure 1).

The support bars 10 are each constructed of a main body portion, as shown, and provided with a depending longitudinal rib 15, which preferably extends diagonally downwardly and forwardly. The lower edge of said flange is provided with a stop shoulder 16. The body of the bar 10 is provided with two longitudinal grooves 17 and 18 in the top and bottom portions respectively. A plurality of catch-supports 19 are provided, and may be constructed of any suitable material. It is

preferred, however, to stamp each of said catch-supports out of sheet metal by cutting out a portion 20, and bending it away from the rest of the body portion so as to provide two gripping jaws 21 and 22, which are equipped with flanges positioned to engage the grooves 17 and 18, above referred to. The catch-supports may be passed over the end of a bar 10, and slid along to the desired position after which they may be left free to slide, or they may be held against movement in suitable manner, as by punching out a portion thereof so as to penetrate the bar 10, as indicated at 23. The free end of the catch-support 19 is provided with parallel ears 24, and the extremity of said end is turned inwardly, as indicated at 25 to a position between said ears. Each member 19 supports a gripper or catch member 26, which is provided with a groove 27 in its under surface near one end, so positioned that it will receive the inturned extremity 25 of the catch-support, said extremity serving as a fulcrum for said pin. A spring 28 having one arm secured to the catch-support 19, as indicated at 29, bears upon the gripper member 26 in such manner as to normally hold its free end in contact with the stop shoulder 16.

In Figure 8 is illustrated a slight modification of the catch-support. Referring to said figure, 30 designates a metal body provided with flanges 31 and 32 to engage the grooves 17 and 19 respectively, the extremity of said member 30 being provided with ears 33, which support a pivot member 34, upon which the gripper pin 35 pivots. A suitable spring 36 serves to maintain the necessary tension upon the gripper pin to hold it in engagement with the stop flange 16.

In practice, any desired number of the rack bars 10 may be assembled, as occasion may require, or but a single one of said bars may be used, or but a single catch member 19, member 26, and body 10 may be employed as may be required. Where a plurality of the bars 10 is employed, the rack may be pivotally and conveniently supported in any desired manner, such as illustrated in Figure 1, so that when it is not in use it may hang down against the wall or other support and be out of the way. In operation, the article to be supported is gripped between the flange 15 and the gripper member 26. In order to engage an article with the gripping elements, the free

end of the gripper member 26 is moved away from the flange 16, against the tension of the spring 28, and a portion of the article is placed over said flange. The gripper member 5 26 is then released and the spring 28 will cause it to firmly grip the article between the end of the pin and the flange 16 in such a manner that it will not readily become disengaged. If, however, it is desired to remove the article, 10 it is only necessary to slightly lift the free end of the gripper member 26, and the article may be withdrawn without difficulty.

The advantages of the invention will be readily understood by those skilled in the art 15 to which it belongs. For instance, it will be readily understood that it may be made up of any desired size to suit different requirements and supported in any convenient location. The gripper members may be made 20 larger or smaller according to the size or character of the goods to be supported. A further advantage is that in view of the fact that nails and pegs are dispensed with, the device may be used for supporting delicate 25 fabrics, such as lace curtains and the like and if desired for this purpose, the catches may be made to slide on the rod for different spacing to suit pins on the casing. Another important advantage is that the gripper members 30 firmly engage any article that is to be supported, so that accidental disengagement is impossible and yet when desired, the article may be released with little effort by slightly elevating the free end of the gripper pin.

35 Having thus explained the nature of the invention and described an operative manner of constructing and using the same, although without attempting to set forth all of the forms, in which it may be made, or all of the forms of its use, what is claimed is:—

40 1. In a rack of the character described, an article gripping device comprising an elongated support member consisting of a body provided with a depending longitudinal rib, 45 a catch support having one end in engagement with and supported by said first mentioned support member, the other end being free and spaced from said rib, and a gripper member movably mounted in the free end of said catch support and positioned to engage said rib, so as to grip an article between said rib and said catch member.

50 2. In a rack of the character described, an article engaging device comprising a support member provided with a depending stop portion, a catch support having jaws at one end constructed to have a slidable engagement with said first mentioned support member and having its free end extending in front of and spaced from said stop portion, and a gripper member movably mounted in the free end of said catch support and positioned to engage the said stop portion, so as to grip the article to be supported between them.

55 3. In a rack of the character described, an

article engaging device comprising a support member provided with top and bottom grooves and a depending stop portion, a catch support having jaws at one end provided with flanges extending into said grooves, said catch support having a downwardly and forwardly inclined body extending in front of and in spaced relation with respect to said stop portion, a gripper member movably supported by the free end of said catch support 75 and positioned to engage said stop portion, and a spring acting to normally maintain said gripper member in engagement with said stop portion.

4. In a rack of the character described, a support provided with a depending stop portion, a catch support extending forwardly and downwardly from said first mentioned support and in spaced relation with respect to said stop portion, the extremity of said 80 catch support being turned inwardly to provide a fulcrum, a gripper member having a grooved portion in one end engaging said fulcrum, and means for yieldably holding said gripper member in engagement with said 85 stop portion.

5. In a rack of the character described, an article engaging device comprising a support provided with a depending stop portion, a catch support extending forwardly and downwardly from said first mentioned support and in spaced relation with respect to said stop portion, said catch support being provided with spaced apart ears and having its lower extremity bent inwardly to a position between said ears, a gripper member 95 pivotally mounted upon said inturned extremity and guided between said ears, and a spring supported by said catch support and acting upon said gripper member to normally hold it in engagement with said depending stop portion.

6. In a rack of the character described, an engaging device comprising a support provided with a depending rib having a stop flange, a catch support having one end provided with jaws engaging said first mentioned support so as to be sustained thereby, said catch support extending forwardly and downwardly from said first mentioned support and provided with spaced apart ears near its lower end, the extremity of said catch support contiguous to said ears being turned inwardly, a gripper member provided with a grooved portion at one end having a movable engagement with the inturned extremity of the catch support, and a spring supported by said catch support and having a portion bearing against said gripper member so as to hold the free end of the gripper member in engagement with said stop flange.

7. A rack of the character described comprising a plurality of article gripping devices each consisting of an elongated support member having a body provided with a depend-

ing rib with a shoulder on one edge thereof, a catch support having one end in engagement with and supported by said support member, the other end being free and spaced 5 from said shoulder, and a gripper member mounted in the free end of said catch support and positioned to engage said shoulder, so as

to grip an article between said shoulder and said catch member, in combination with means for maintaining a plurality of said support members in spaced relation.

In testimony whereof I have hereunto set my hand.

ROBERT A. McCALL.
